Primary Examiner—Celia A. Murphy

CLAIM

We claim the ornamental design for a box for compact discs, as shown and described.

DESCRIPTION

Box for holding media compact discs.

FIG. 1 is a top plan view of a box for compact discs, in closed condition, showing our new design;

FIG. 2 is front elevation view thereof;

FIG. 3 is a bottom plan view thereof;

FIG. 4 is a rear elevation view thereof;

FIG. 5 is a side elevation view thereof, the sides being mirror images of one another;

FIG. 6 is a side elevation view of the box of FIG. 1, in an open condition;

FIG. 7 is top plan view thereof; and,

FIG. 8 is an isometric view thereof.

1 Claim, 5 Drawing Sheets
